DESIGN FOR A HANDBAG

Louis Kaufman, New York, N. Y.

Application August 14, 1948, Serial No. 148,117

Term of patent 7 years

(Cl. D87—3)

To all whom it may concern:

Be it known that I, Louis Kaufman, a citizen of the United States of America, residing in New York city, county of New York, and State of New York, have invented a new, original, and ornamental Design for a Handbag, of which the following is a specification, reference being had to the accompanying drawing, forming part thereof, wherein,

Figure 1 is a front elevational view of a handbag, showing my new design, in closed position.

Figure 2 is a side elevational view.

Figure 3 is a top plan view with a portion of the handle omitted for convenience of illustration.

Figure 4 is a view similar to Figure 1, showing the front portion in turned down position, and showing a portion of the handle omitted for convenience of illustration.

Figure 5 is a side elevational view of Figure 4, showing the compartment and drawer members in open position.

The rear view of the closed handbag is identical in appearance to the front shown in Figure 1, except for the omission of the closure member.

I claim:

The ornamental design for a handbag, substantially as shown and described.

LOUIS KAUFMAN.
